INTERNAL NOZZLE FOR TEMPERING
BOTTLES AND OTHER GLASS CON-
TAINERSCharles E. Mongan, Jr., Hartford, Conn., as-
signor to Hartford-Empire Company, Hart-
ford, Conn., a corporation of Delaware

Application April 26, 1941, Serial No. 390,591

8 Claims. (Cl. 299—137)

This invention relates to improvements in nozzles for discharging cooling fluid against the internal surface of a bottle or other glass container to effect tempering of such bottle or container or some other desirable result.

It has been found by experiments that desirable tempering of a bottle or other glass container may be most satisfactorily accomplished by the use of a nozzle having fluid coolant discharge orifices of a particular size or of particular sizes at different places along the length of the nozzle according to the particular shape and size or other characteristics of the particular bottle or container that is to be tempered, the pressure on and the kind of fluid coolant employed, etc. Also, it may be desirable to have different spaces between adjacent discharge orifices in different portions of the body of such a nozzle. For bottles or containers of different types or even for bottles or containers of different sizes of the same general type, nozzles individually different insofar as the size or sizes of certain or all of their discharge orifices and as to the spacing of the respective discharge orifices are concerned, may be most suitable. In other words, it may be stated as a general proposition that for each size or type of bottle or container, a nozzle having discharge orifices of a particular size or of particular sizes and of a particular relative arrangement is best suited for the application to the interior of such bottle or container of a cooling fluid of a given kind and under a given pressure.

An object of the present invention is to obviate the necessity of providing completely different nozzles for different sizes and/or different types of bottles and other glass containers in order to use in each instance a nozzle believed to be most suitable for application of a cooling fluid, such as air, to the interior of the particular bottle or container to be tempered.

A further object of the invention is to provide a nozzle of the character described having a construction which will permit the removal and replacement of the portion or portions of the nozzle containing the discharge orifices without thereby necessitating alteration of the remainder of the nozzle or any disturbance of its operating connection with other parts of a tempering machine or apparatus to which such nozzle has been applied.

A further object of the invention is to provide a nozzle of the character described having an elongate tubular body provided with one or more quickly and easily removable and replaceable elongate coolant discharge sections.

A further object of the invention is to provide a nozzle of the character described having one or more readily removable and replaceable discharge sections extending for a substantial part of the length of the body of the nozzle when in cooperative relation therewith and each of such a construction that the pressure of cooling fluid within the nozzle body tends to maintain such section or sections in place with relation to the remainder of the nozzle body.

Other objects and advantages of the invention will hereinafter be pointed out or will become apparent from the following description of a practical embodiment of the invention, as shown in the accompanying drawing in which:

Fig. 1 is a view, partly in vertical section and partly in elevation, showing my novel nozzle operatively supported in relation to a glass bottle that is to be tempered;

Fig. 2 is a relatively enlarged longitudinal vertical section through a portion of the nozzle body and the nozzle tip, substantially along the line indicated at 2—2 of Fig. 1;

Fig. 3 is a still further enlarged transverse section through the nozzle body substantially along the line 3—3 of Fig. 2;

Fig. 4 is a view showing in elevation a fragmentary portion of the nozzle body, with an outer layer portion of the nozzle body partially broken away to reveal underlying parts; and

Fig. 5 is a vertical section through the tip and adjacent portion of the nozzle body substantially along the line 5—5 of Fig. 3, but on a relatively reduced scale.

A nozzle embodying the invention may comprise an open ended tubular body 10 formed of any suitable metal or other material. This body 10 may be provided with one or more longitudinally extending dove-tailed slots 11 extending from the free end thereof for a substantial part of the length of the body, as for a sufficient part of such length to adapt the nozzle body for use in the tempering of bottles and other glass containers having substantially different heights. As shown, the nozzle body 10 has two of the dove-tailed slots 11, these respectively being located diametrically opposite each other as best seen in Fig. 3.

Each of such dove-tailed slots may be open throughout the full length and width thereof at the inner surface of the body 10. The bottom wall of each dove-tailed slot 11 may be provided with a series of aligned elongate openings or slits 12, formed in the longitudinal median portion thereof to extend in the direction of length of the nozzle body. The respective elongate open-

ings or slits 12 of the series at the bottom of each dove-tailed slot 11 may be of the same or of individually different lengths and each may be spaced at one end from the adjacent elongate opening or slit by an imperforate portion of the dove-tailed bottom wall or land as indicated at 13. When the nozzle body is provided with a plurality of the dove-tailed slots, as in the example shown in the drawing, the generally corresponding imperforate portions or lands 13 for the several dove-tailed slots may be located at different places along the lengths of such slots or staggered so as to cause overlapping vertically of the elongate openings or slits 12 at the bottoms of the several slots 11. This is shown to advantage in Fig. 2.

A removable and replaceable slide member 14 in the form of an elongate strip or ribbon of a suitable material, such as phosphor-bronze, for example, is provided for each of the dove-tailed slots 11. Such strip is provided with longitudinally spaced jet holes or discharge openings 15. These may be arranged in a number of longitudinally spaced series so as to leave the portions of the strips beneath the lands 13 imperforate or any selected or preferred relative arrangement or spacing of the respective jet holes or discharge openings 15 may be employed. All these openings 15 may be of the same size or certain of them may be of sizes different from the others. The controlling factor will be the cooling pattern or curve to be obtained by discharge of cooling fluid, such as air, from the nozzle body through the strip against different portions of the inner surface of a bottle, such as that indicated at B in Fig. 1, or other glass article that is to be tempered.

The strips 14 may be formed of a material having sufficient flexibility and spring qualities to be compressed laterally to a slight extent between the side walls of the dove-tailed slot in which such strip is disposed (see Fig. 3). The strip may be inserted end-wise into the slot at the open end of the nozzle body. The tip of the nozzle, indicated at 16, may be removed to permit convenient manipulation of the strip in effecting such insertion.

If a relatively flexible strip of slight thickness is employed, as shown in the example, such strip may have its outer end portion bent inwardly, as indicated at 14a to project into an annular groove 17 in the periphery of the tip 16 when the latter has been applied to the nozzle. This tip may have a substantially hemispherical head portion and a relatively short tubular attaching body portion adapted to fit within the free end portion of the nozzle body and to be fastened in place in any suitable way, as by means of the screws 18, Figs. 3 and 5. As best seen in Fig. 2, pins 19 may project from the tip 16 at the part thereof containing the peripheral groove 17 against the inturned end portions 14a of the strips. These pins extend radially outward from the tip at least to the planes of the strips so that such pins may be employed to retain such strips against accidental sliding movements relative to the body in the direction of the tip even though such strips be formed without the inturned end portions 14a. These inturned end portions of the strips may serve to cooperate with the nozzle tip to retain the strips against accidental longitudinal displacement in either direction from their inserted positions in the slots of the nozzle body.

Instead of a strip of the narrow gauge material indicated by the showing of the strips 14 in 75

the drawing, thicker and less flexible strips or segments may be provided. These may be formed either with or without inturned outer ends corresponding to the ends 14a of the strips 14.

5 As many different kinds of strips may be provided for use at different times with the same nozzle body as there are different kinds of bottles or other glass articles to be tempered by the use of tempering apparatus including such nozzle. Each such strip may have its own particular arrangement of jet holes or discharge openings of the particular size or sizes and location which will best adapt that strip for use as a coolant discharge member for applying the coolant to the interior of a bottle or glass container of a particular size, shape or type.

As shown, the tip 16 has discharge orifices 20 extending radially in three different rows from the center of the forward part of the tip, these rows being equidistant apart as best seen in Fig. 3. The attaching portion of the tip is shown as also having openings 21 to permit passage in lateral directions of coolant from the interior of the tip to certain of the openings in the adjacent portions of the strips 14. It is to be understood that nozzle tips having different discharge openings or different arrangements of discharge openings may be provided and used interchangeably so that the tip having the most suitable cooling fluid discharge provisions for a particular cooling fluid discharge strip or strips may be used with such strip or strips.

The nozzle body 10 is shown in the drawing as having been formed of concentric inner and outer tubular members but these may be made in one piece. The attaching portion of the nozzle tip likewise is shown as having a separately formed outer ring member which may be integral with the remainder of such tip.

The nozzle body 10 may be supported for rotation about its longitudinal axis by any suitable known means. I prefer however to make use of a structure which will steady such nozzle against lateral oscillations and wobbling. As shown in Fig. 1, the nozzle body is connected by screw threads at 22 with a nipple 23 which carries a driving gear or pinion 24. The nipple 23 is connected by screw threads at 25 with a tubular suspension member 26 which has an out-turned flange 27 supported anti-frictionally, as by the ball bearing assembly 28, within the relatively enlarged upper end portion 29 of a supporting sleeve 30 which is mounted in a suitable opening in a stationary frame member 31. The nozzle body 10 is further stayed and rotatably supported at a lower level by the vertically disposed needle bearing unit 32 which is mounted on the nozzle body 10 between the retaining rings 33 and 34. The bearing unit 32 includes an outer tubular member 35 which extends vertically through a suitable opening 36 in a stationary frame member 37 and has an outturned flange 38 resting upon the frame member 37, so that the bearing unit is supported by the latter.

65 It will be understood that a nozzle embodying the present invention may be used with any suitable means, none being shown, for applying coolant to the external surface of a bottle or other glass container that is being cooled internally by the use of such nozzle.

I claim:

1. A nozzle of the character described comprising an elongate tubular body having a longitudinally extending slot in a portion thereof, said slot being open at the interior of said tubular

body, said tubular body having an elongate aperture in the bottom of said slot of less width than said slot and open at the outer periphery of said tubular body, and a removable and replaceable elongate slide member fitting in said slot and having a series of jet holes formed therein in communication with the elongate aperture in the bottom of said slot.

2. A nozzle of the character described comprising an elongate tubular body, said elongate body having a dove-tailed slot formed in a portion thereof from the outer end of said body for part of the length thereof, said dove-tailed slot being open throughout its length at the interior of said nozzle body, said nozzle body having a longitudinally extending series of relatively narrow elongate apertures formed in the bottom of said dove-tailed slot, and an elongate strip adapted to be inserted at the outer end of said nozzle body end-wise into said dove-tailed slot to fit therein against the bottom of said dove-tailed slot, said strip having series of jet holes in the portions thereof within in the confines of said elongate relatively narrow apertures in the bottom of said slot.

3. A nozzle of the character described comprising an elongate tubular body, said body having a plurality of angularly spaced longitudinally extending dove-tailed slots opening through the inner wall of the body and also open at the outer end of said body, said body having longitudinal series of aligned elongate relatively narrow apertures in the bottom walls of said slots, corresponding elongate apertures in the bottoms of the respective slots being staggered so as to overlap longitudinally of the nozzle body, removable and replaceable slide strips adapted to be inserted end-wise at the outer end of the nozzle body into said slots and to fit therein against the bottoms of said slots, said slide strips having spaced jet holes formed therein for discharging cooling fluid from the interior of the nozzle body through said elongate relatively narrow apertures.

4. A nozzle of the character described comprising an elongate tubular body, said body having a plurality of angularly spaced longitudinally extending dove-tailed slots opening through the inner wall of the body and also open at the outer end of said body, said body having longitudinal series of aligned elongate relatively narrow apertures in the bottom walls of said slots, corresponding elongate apertures in the bottoms of the respective slots being staggered so as to overlap longitudinally of the nozzle body, removable and replaceable slide strips adapted to be inserted end-wise at the outer end of the nozzle body into said slots and to fit therein against the bottoms of said slots, said slide strips having spaced jet holes formed therein for discharging cooling fluid from the interior of the nozzle body through said elongate relatively narrow apertures, and a removable nozzle tip structure connected with the nozzle body at the outer end thereof and having spaced openings in the walls thereof for the discharge of cooling fluid.

5. A nozzle of the character described comprising an elongate tubular body, said body having a plurality of angularly spaced longitudinally extending dove-tailed slots opening through the inner wall of the body and also open at the outer end of said body, said body having longitudinal series of aligned elongate relatively narrow apertures in the bottom walls of said slots, correspond-

ing elongate apertures in the bottoms of the respective slots being staggered so as to overlap longitudinally of the nozzle body, removable and replaceable slide strips adapted to be inserted end-wise at the outer end of the nozzle body into said slots and to fit therein against the bottoms of said slots, said slide strips having spaced jet holes formed therein for discharging cooling fluid from the interior of the nozzle body through said elongate relatively narrow apertures, and a removable nozzle tip structure connected with the nozzle body at the outer end thereof and having spaced openings in the walls thereof for the discharge of cooling fluid, said tip having a peripheral groove adjacent to the outer end of the nozzle body and said slide strips having inturned outer end portions projecting into said peripheral groove.

6. A nozzle of the character described comprising an elongate tubular body, said body having a plurality of angularly spaced longitudinally extending dove-tailed slot openings through the inner wall of the body and also open at the outer end of said body, said body having longitudinal series of aligned elongate relatively narrow apertures in the bottom walls of said slots, corresponding elongate apertures in the bottoms of the respective slots being staggered so as to overlap longitudinally of the nozzle body, removable and replaceable slide strips adapted to be inserted end-wise at the outer end of the nozzle body into said slots and to fit therein against the bottoms of said slots, said slide strips having spaced jet holes formed therein for discharging cooling fluid from the interior of the nozzle body through said elongate relatively narrow apertures, a removable nozzle tip structure connected with the nozzle body at the outer end thereof and having spaced openings in the walls thereof for the discharge of cooling fluid, said tip having means for engaging with the outer ends of said slide strips to retain them against unintended longitudinal displacement in said slots.

7. A nozzle of the character described comprising an elongate hollow body having longitudinally extending series of differently located spaced cooling fluid discharge openings at a plurality of angularly spaced places around the periphery of said body, and means for supporting said body in vertical position for rotation about the longitudinal axis of the body, said means including a plurality of vertically spaced supported anti-friction bearing assemblies and rigid members rigidly connected together and to said hollow body and respectively journaled in said bearing assemblies for supporting said body for said rotation and for retaining it against lateral oscillatory movements during its said rotation.

8. A nozzle of the character described comprising an elongate tubular body having a longitudinally extending elongate opening in a portion thereof and having also a longitudinally extending open-bottomed slot in open communication at its bottom opening with said elongate opening for the full length of the latter, said slot being open at one end of said tubular body, and an elongate strip adapted to be inserted into said slot at the open end of the latter and to be slid end-wise in said slot to position to serve as an internal closure for said elongate opening, said strip having jet holes in the portion thereof that closes said elongate opening.
